CLAIM

I claim the ornamental design for a packaging for shoes and accessory, as shown and described.

DESCRIPTION

FIG. 1 is a perspective view of the packaging for shoes and accessory.

FIG. 2 is a front elevation view thereof.

FIG. 3 is a rear elevation view thereof.

FIG. 4 is a right-side elevation view thereof.

FIG. 5 is a left-side elevation view thereof.

FIG. 6 is a bottom plan view thereof with a bottom insert removed.

FIG. 7 is a top plan view thereof with the bottom insert removed; and,

FIG. 8 is a perspective view of the packaging for shoes and accessory received in a shoebox.

The broken lines showing a bottom insert in FIGS. 1-5 and 8 represent portions of the packaging for shoes and accessory. The broken lines showing a shoebox in FIG. 8 represent environmental structure. The broken lines form no part of the claim.
